UNITED STATES PATENT OFFICE

ARTHUR R. FREDERICKS, OF LOS ANGELES, CALIFORNIA, ASSIGNOR TO JOSEPH POWERS, OF OXNARD, CALIFORNIA

STAGE SETTING

Application filed September 10, 1928. Serial No. 305,080.

This invention particularly relates to stage settings and the like, and is concerned with settings of the general character disclosed in Patent No. 1,548,522 issued to me August 4, 1925.

Until the advent of the type of stage setting disclosed in my above-mentioned patent, it was common practice in most instances, to provide large and cumbersome sets and drops which were heavy and required considerable stage help for their manipulation and adjustment. Other sets including drop curtains and wings have been designed which require the operation of complicated lifting 10 rigging for the manipulation of heavy carriage members and counter weights and the units of which are not independently operable.

By the use of the type of apparatus which 20 I have designed it is possible to provide stage settings which are quite flexible as to their operation, adjustment and adaptation to the demands of different dramatic productions, and make it possible to rapidly change sets 25 and to adapt the various elements of the sets to the subject at hand with small effort. The principal object of the present invention, therefore, is to provide stage settings which may be readily moved across the stage; may 30 be instantly and conveniently set at any angle to the back of the stage, and may be manipulated and readily altered to provide fragmentary or composite stage effects not now conveniently possible.

35 The present invention contemplates the use of a fixed overhead trackway upon which carriages may be independently operated and which carriages carry panels adapted to be readily adjusted around a vertical axis to 40 assume a desired angular position with relation to the stage setting and adapted to be completely reversed to present another stage set, or to be adjusted to accommodate doors, walls or other pieces of scenery.

45 The invention is illustrated by way of example in the accompanying drawing, in which:

Fig. 1 is a view in vertical section and elevation showing the complete device with 50 which the present invention is concerned.

Fig. 2 is a view in transverse section through the overhead track showing the manner in which the carriage is adapted to move therealong.

Fig. 3 is a view in section through the certain hanger frame as seen on the line 3—3 of Fig. 1.

Fig. 4 is a fragmentary view in plan showing the manner in which the panel may be angularly disposed around a vertical axis.

Fig. 5 is a view in elevation showing the manner in which the present device may be adapted for use in framing openings.

Fig. 6 is a view in horizontal section and elevation as seen on the line 6—6 of Fig. 1, showing the clutch ring mechanism.

Referring more particularly to the drawing, 10 indicates an overhead track which is in the form of a box girder comprising a plank 11, side planks 12 and 13 and track strips 14 and 15. The girder thus formed is permanently secured to rafters 16 or the overhead grid of the proscenium arch. Disposed within the girder is a carriage 17 having sets of rollers 18 near its opposite ends and on opposite sides thereof. These rollers are intended to move along, and to be supported by the track strips 14 and 15. The carriage is moved by an operating rope 19 which is secured by its opposite ends within the girder and adjacent the opposite ends thereof. This rope is lead over sheaves 20 and 21 disposed between the longitudinal frame members 22 of the carriage and between the rollers 18. It will be evident that by pulling in one direction on the downwardly hanging looped portion of the rope 19 the carriage will move longitudinally of the girder 11, and when pulled on the opposite side of the looped portion of the rope 19, will move in the other direction. It will therefore be evident that by very simple manipulation and without the use of counterweights, the overhead carriage may be moved to a desired position and set.

Dependent from the center of the carriage frame members 22 and extending downwardly through the slotted opening 23 between the track strips 14 and 15 is a hanger 24. This hanger carries an adjusting standard 100

25 upon which a panel unit 26 is mounted. The standard 25 is in the form of a tube vertically disposed, and upon which the panel unit 26 is vertically adjustable. This unit 5 comprises a cross-beam 27 having opposite side bars 28 and 29 between which the tube 25 extends. A grip ring 30 is carried between the members 28 and 29 and the standard 25 directly extends through this ring. 10 The construction of the ring is more clearly shown in Fig. 6 of the drawing, where it will be seen that the ring 30 is provided with a biting edge 31 adapted to impinge against one side of the standard 25 and to be held in this position by a spring 32 fastened to a permanent support 33 held by the cross-member 27. The ring 30 and the spring 32 are connected by a suitable link 33, which link may be actuated by a lever 34 to release the 15 tension of the spring 32, and to permit the panel unit to move down along the standard; it being understood that the formation of the grip ring 30 is such as to permit free movement of the panel unit upwardly along 20 the standard when the unit is lifted. The lever 34 is mounted upon the cross-beam 27 of the panel by a pivot bracket 35. Its free end carries a cable 36 which is rove around a pulley 37 at the center of the cross-beam 27. 25 This cable extends upwardly over a pulley 38 carried by the carriage frame members 22 and is then lead downwardly into the tubular standard 25 where it engages a counterweight 39. This weight substantially equals the 30 weight of the panel unit 27 and will counterbalance the same. A cable 40 is secured to the lower end of the counterweight and extends downwardly through a cap 41 mounted on the bottom of the standard 25. 35 A rubber block 42 is supported at the bottom end of the standard by the cap and will act to provide a resilient stop for the counterweight 39 if this weight should become disconnected from the cable 36. The free end of the cable 40 is secured to a free end of the 40 clutch lever 34 so that the lever may be manipulated to release the ring 30 and to permit the panel to fall as resisted by the counterweight 39. 45 In order to resiliently support the panel unit and to prevent excessive shock being delivered to it, springs 43 are secured to the upwardly extending length of the cable 36 to engage the cross-beam 27 at opposite sides 50 of its central vertical axis. This will tend to steady the cross-beam and to prevent undue strain on the clutch mechanism. 55 Carried by the opposite frame members 28 and 29 of the panel cross-beam 27 are certain hanging rods 44 and 45, as clearly shown in Fig. 3 of the drawing. 60 It will thus be evident that the present invention contemplates the hanging of two different curtains on the one panel unit so 65 that this unit may be reversed to obtain an

entirely different result, if desired. It is preferable that the curtains be provided with rings or hooks as indicated at 46, so that they may be readily detached from the rod and moved therealong. It may be desirable 70 to make the drop in one width, or if preferred it may be made in a plurality of sections, as, for example, shown in Fig. 5 of the drawing, where it is in two sections, separated to provide an opening through the 75 panel unit for the purpose of accommodating door or window frames, or separate scenic sets.

Hangers 47 are carried upon the side frame members 28 and 29 of the cross-beam 27, and 80 may receive supplemental scenic units 48 which may be disclosed by shoving the main curtain panels 49 or 50 to one end or opposite ends of the cross-beam 27.

After the set has been installed, as indicated in the drawing, by permanently securing the box girder to the arch, and after the carriages 22 have been mounted on the track-way of the girders, the stage setting may 85 then be operated.

Attention is directed to the fact that in the present instance the overhead trackway is permanently fixed, as this is in contradistinction to devices having trackways which require vertical adjustment to raise and lower 90 the panels. It is also to be understood that a plurality of carriages 22 with their associated panel units 26 may be mounted upon the said trackway, and in any event these units will be capable of independent movement with relation to each other.

The panel unit may now be lowered by pulling on the cord 40 to swing the lever 34 and to release the clutch ring 30 from engagement with the standard 25. This will permit the panel to be lowered as it overcomes the inertia of the counterweight 39 which is disposed within the standard 25. After the unit has been lowered any desired arrangement of curtains or hangings may be placed 100 upon the rods 44 and 45. These may be so arranged as to provide a wing of solid color or to carry a panel having some scenic design thereon. At this time the supplemental panels 48 may be mounted upon the hangers 47 so that rapid manipulation of the outer panels 49 will permit the supplemental panels to be used either in conjunction therewith or after the main hangings 49 have been removed from the rods.

A particular adaptation of the present invention is shown in Fig. 5 where it will be seen that the main hangings 49 are separated to disclose a scene painted upon the supplemental hanging 48. It will, of course, be evident that the hangings 48 and 49 may be completely removed, in which instance an opening will be formed through the set.

After the proper curtains, screens or panels are mounted upon the sides of the cross-

beam 27, the cord 40 may again be pulled. This time to exert the pull on the lower end of the counterweight 39 and to act through the cord 35 to lift the panels unit with relation to the standard 25.

At any point along the standard that a release of the pull on cord 40 occurs, the clutch ring 30 will bite into the side of the standard 25 and will hold the panel in this vertically adjusted position. It is then possible to move the assembled panel unit across the stage on the carriage 22 by pulling on the operating rope 19 which will shift the panel in either direction. As here shown, the rope 19 extends downwardly through the outer ends of the cross-beam 27 of the panel to be concealed by the panel with the surplus amount of rope lying upon the floor. With the rope in this position it is possible to use it to manipulate the cross-beam 27 and to rotate this beam in a horizontal plane around the vertical axis defined by the standard 25. In this manner the panel unit may be moved in either direction horizontally as indicated by the arrow "a" in Fig. 4.

It will also be evident that when it is desired to rapidly reverse the panel to transform the set that a complete half horizontal rotation of the panel may be effected to present the curtain 50 or the hanging 48 to view.

It will thus be seen that by the construction here provided it is possible to provide a stage setting which may be permanently installed on a stage without the necessity for skilled labor and which, when installed, may be easily operated without the use of heavy and dangerous counterweights or the use of complicated rigging to lift or shift the various elements of the structure, and it will further be noted that by the operating mechanism here disclosed, the panel may be entirely manipulated at the panel without requiring that at least one operator shall be stationed at one side of the stage to operate a lifting or shifting rig.

While I have shown the preferred form of my invention as now known to me, it will be understood that various changes may be made in the combination, construction and arrangement of parts by those skilled in the art, without departing from the spirit of the invention as claimed.

Having thus described my invention, what I claim and desire to secure by Letters Patent is:—

1. A stage setting comprising a box girder extending transversely of the stage and being permanently fixed adjacent the proscenium arch, a trackway carried by said girder, a carriage having rollers mounted on the trackway and upon which the carriage may roll back and forth across the stage, a panel unit dependent from said carriage and a flexible operating member secured by its ends to op-

posite ends of the trackway and being looped downwardly between points on the carriage whereby a pull on one side of said loop will cause the carriage to move toward that end of the flexible operating member and a pull upon the opposite side of the loop will cause it to move toward the opposite end of the flexible operating member.

2. A stage setting comprising a box girder extending transversely of the stage and being permanently fixed adjacent the proscenium arch, a trackway carried by said girder, a carriage having rollers mounted on the trackway and upon which the carriage may roll back and forth across the stage, a panel unit dependent from said carriage and a flexible operating member secured by its ends to opposite ends of the trackway and being looped downwardly between points on the carriage whereby a pull on one side of said loop will cause the carriage to move toward that end of the flexible operating member and a pull upon the opposite side of the loop will cause it to move toward the opposite end of the flexible operating member and means disposed adjacent the panel for vertically adjusting the same with relation to the floor of the stage.

3. A stage setting comprising a box girder extending transversely of the stage and being permanently fixed adjacent the proscenium arch, a trackway carried by said girder, a carriage having rollers mounted on the trackway and upon which the carriage may roll back and forth across the stage, a panel unit dependent from said carriage and a flexible operating member secured by its ends to opposite ends of the trackway and being looped downwardly between points on the carriage whereby a pull on one side of said loop will cause the carriage to move toward that end of the flexible operating member and a pull upon the opposite side of the loop will cause it to move toward the opposite end of the flexible operating member, means disposed adjacent the panel for vertically adjusting the same with relation to the floor of the stage and a grip member by which the panel may be held in its vertically adjusted position while permitting rotation of the panel around the vertical axis thereof.

4. A stage setting comprising a panel unit including a cross-beam, screens hung therefrom, a standard secured adjacent the grid of the stage and extending vertically to receive the cross-beam, a counterweight mounted within the standard, a cable secured to the upper end of the counterweight by one end, and to the cross-beam by the other, whereby the beam will be substantially counterbalanced, and another cable for manipulating the cross-beam and the counterweight to vertically adjust the cross-beam.

5. A stage setting comprising a panel unit including a cross-beam, screens hung there-

from, a standard secured adjacent the grid of the stage and extending vertically to receive the cross-beam, a counterweight mounted within the standard, a cable secured to the upper end of the counterweight by one end, and to the cross-beam by the other, whereby the beam will be substantially counterbalanced, another cable for manipulating the cross-beam and the counterweight to vertically adjust the cross-beam and means for automatically gripping the cross-beam in a desired vertical position as the cross-beam and the hangings thereon are lifted.

6. A stage setting comprising a panel unit including a cross-beam, screens hung therefrom, a standard secured adjacent the grid of the stage and extending vertically to receive the cross-beam, a counterweight mounted within the standard, a cable secured to the upper end of the counterweight by one end, and to the cross-beam by the other, whereby the beam will be substantially counterbalanced, another cable for manipulating the cross-beam and the counterweight to vertically adjust the cross-beam and means for automatically gripping the cross-beam in a desired vertical position as the cross-beam and the hangings thereon are lifted, and means for releasing said gripping device to permit the panel unit to be lowered as it overcomes the weight of the counterweight.

ARTHUR R. FREDERICKS.
